[57] **CLAIM**

The ornamental design for a wheeled standing platform for a baby carriage or stroller, as shown and described.

DESCRIPTION

FIG. 1 is a rear perspective view showing top view, left side and rear view of a wheeled standing platform for a baby carriage or stroller, with the wheels removed, showing my new design;

FIG. 2 is a top perspective view showing the top view and left side view;

FIG. 3 is a rear side perspective view, showing the rear view and right side view thereof, with the wheels removed;

FIG. 4 is a bottom plan view thereof, with the wheels removed;

FIG. 5 is a bottom perspective view, showing the front view thereof, with the wheels removed;

FIG. 6 is a top perspective view, showing the rear view thereof, with the wheels removed; and,

FIG. 7 is a front perspective view thereof, with the wheels removed.

The left side view is a mirror image of the right side view.
